CHEMICAL TESTING KIT

Paul H. Dutch, 4500 La Barca Drive,
Tarzana, Calif. 91356

Filed Nov. 25, 1968, Ser. No. 14,647

Term of patent 14 years

Int. Cl. D24—02; D9—04

U.S. Cl. D16—1

Fig. 1.

Fig. 2.

Fig. 3.

Fig. 4.

Fig. 5.

Fig. 7.

Fig. 6.

FIG. 1 is a front elevation of the chemical testing kit showing my new design;

FIG. 2 is a rear view thereof;

FIG. 3 is a side edge view thereof;

FIG. 4 is a bottom edge view thereof;

FIG. 5 is a top edge view thereof;

FIG. 6 is a view thereof taken along lines 6—6 of FIG. 2; and

FIG. 7 is a rear perspective view thereof.

I claim:

The ornamental design of a chemical testing kit, as shown.
